UNITED STATES PATENT OFFICE.

CARMON A. MYERS, OF AKRON, OHIO, ASSIGNOR TO THE FIRESTONE TIRE AND RUBBER COMPANY, OF AKRON, OHIO, A CORPORATION OF OHIO.

CALENDER CONSTRUCTION.

1,406,062.

Specification of Letters Patent. Patented Feb. 7, 1922.

Application filed January 3, 1921. Serial No. 434,423.

To all whom it may concern:

Be it known that I, CARMON A. MYERS, a citizen of the United States, residing at Akron, in the county of Summit and State of Ohio, have invented certain new and useful Improvements in Calender Constructions, of which the following is a specification.

This invention relates to the construction 10 of machine frame work which is adapted for use where the interior of the machine or the adjacent region requires ventilation. The particular embodiment of my invention shown and described is in the construction 15 of a calender frame for calendering rubber stock and the necessity for ventilation arises both from the heat radiated from the heated calender rolls and from the gases given off from the rubber in the calendering operation.

Although my invention is shown in this special embodiment, it is not so limited, but the principles thereof may be used in other connections and relationships. Also the details of construction shown and described 25 may be varied and modifications may be made within the scope of the invention without departing therefrom.

In the drawings accompanying this application, is shown one form of the invention as applied to a ventilating system for calenders, in which—

Fig. 1 is a vertical section through the calender showing the means used for exhausting or ventilating it.

Fig. 2 is an enlarged section taken at right angles to Fig. 1, but showing the calender only.

Fig. 3 is a horizontal section through the 40 calender frame at about its midway point.

In the showing of this application many of the parts of the conventional or well-known rubber calender have been omitted, as they are well known in the art, others 45 have been dotted in to show their relationship to the invention.

The calender frame work comprises two standards of approximately A-shape construction, the legs 2 being hollow to provide 50 passageways 3 for ventilating purposes. Across the upper ends of the standards are

arranged two U-shaped hollow castings 4 which are bolted to the framework around correspondingly shaped openings or notches in the top of the standards so that the castings communicate with the hollow legs of the standards. Over the top of the calender and overhanging the top roll is arranged a hood 5 which fits closely within the space between the standards so that all of the hot air and gases arising from the rolls are collected underneath it. The hood fits closely over the top of the trough-shaped castings 4, the upper edges of the castings being provided with notches 6, so that the air 60 and fumes assembled in the hoods may be gathered into the trough-shaped collectors and thence taken into the hollow standards. The notches 6 are shown as somewhat deeper toward the outside of the trough than toward the inside of the framework, but this arrangement or the location of the apertures may be varied if desired.

The passageways 2 in the standards are placed over passageways 7 in the foundation 75 which communicate with a duct 8, which is in turn connected with any suitable suction means. The duct 8 may be common to a row of calenders, if desired.

By the mechanism shown, the gases which 80 are desired to be removed, are drawn out of the hood through the collectors 4, down the standards and out through the duct 8.

This provides a convenient and inexpensive method of ventilating the calender room 85 by drawing off the air and other gases directly at the calender.

Apertures 9 in the top of the standard, normally closed by covers 10, and apertures 11 in the sides of the framework, normally 90 closed by covers 12, provide means by which the frame may be cleared out periodically to remove the deposits left by the hot gases.

It is obvious that changes and modifications may be made in form or proportions 95 without sacrificing any of the benefits of the invention.

I claim:

1. In a calender construction, means for 100 ventilating the calender, comprising a hollow calender framework, a hood in the upper part of the calender, means within the hood

for collecting the air under the hood and delivering it to the interior of the calender framework, and suction means connected with the interior of the framework.

5 2. In a calender construction, means for ventilating the calender, comprising a hollow calender framework, a hood in the upper

part of the calender, a trough-shaped collector, extending transversely of the calender, the sides of said collector being apertured 10 and the ends communicating with the hollow framework, and suction means connected with the interior of the framework.

CARMON A. MYERS.
